US00D922000S

(12) **United States Design Patent** (10) **Patent No.:** **US D922,000 S**
(45) **Date of Patent:** **** Jun. 8, 2021**

(54) **PET FEEDER**

(71) Applicant: **HUIZHOU PENGSHA HOME FURNISHING TECHNOLOGY CO., LTD.**, Huizhou (CN)

(72) Inventor: **Deng Peng**, Huizhou (CN)

(73) Assignee: **HUIZHOU PENGSHA HOME FURNISHING TECHNOLOGY CO., LTD.**, Huizhou (CN)

(**) Term: **15 Years**

(21) Appl. No.: **29/774,260**

(22) Filed: **Mar. 15, 2021**

(51) LOC (13) Cl. **30-03**

(52) U.S. Cl.

Primary Examiner — Susan Moon Lee

(57) **CLAIM**

The ornamental design for a pet feeder, as shown and described.

DESCRIPTION

FIG. 1 is a perspective view of a pet feeder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the pet feeder where the pet feeder is in a first configuration of use; and,

FIG. 10 is a perspective view of the pet feeder where the pet feeder is in a second configuration of use.

The broken lines in the drawings depict portions of the pet feeder that form no part of the claimed design.

1 Claim, 10 Drawing Sheets
